US00D900836S

(12) **United States Design Patent** (10) Patent No.: **US D900,836 S**
Burnell et al. (45) Date of Patent: **** Nov. 3, 2020**

(54) **DISPLAY SCREEN OR PORTION THEREOF WITH GRAPHICAL USER INTERFACE FOR INTERACTIVE GUIDELINES FOR MULTIDISCIPLINARY CANCER TREATMENT PLANNING**

(71) Applicant: **Roche Molecular Systems, Inc.**, Pleasanton, CA (US)

(72) Inventors: **Stephen Burnell**, Santa Cruz, CA (US); **Oluwatosin Oyeniran**, San Jose, CA (US); **Mark M. Morita**, Morgan Hill, CA (US); **Amelia E. Schladow**, Tucson, AZ (US); **Weng Chi Lou**, Tucson, AZ (US)

(73) Assignee: **Roche Molecular Systems, Inc.**, Pleasanton, CA (US)

(**) Term: **15 Years**

(21) Appl. No.: **29/615,885**

(22) Filed: **Aug. 31, 2017**

(57) **CLAIM**

The ornamental design for a display screen or portion thereof with graphical user interface for interactive guidelines for multidisciplinary cancer treatment planning, as shown and described.

DESCRIPTION

The FIGURE is a front view of display screen or portion thereof with graphical user interface for interactive guidelines for multidisciplinary cancer treatment planning showing our new design.

The broken lines in the drawing showing the display screen or portion thereof and the remainder of the graphical user interface form no part of the claimed design.
